UNITED STATES PATENT OFFICE

RICHARD J. NACHTIGALL, OF PHILADELPHIA, PENNSYLVANIA, ASSIGNOR OF TWO-FIFTHS TO ALADAR MIKULKA, OF PHILADELPHIA, PENNSYLVANIA

DESIGN FOR A FIREPLACE CABINET

Application filed January 29, 1931. Serial No. 38,472. Term of patent 14 years

To all whom it may concern:

Be it known that RICHARD J. NACHTIGALL, a citizen of the United States, residing at Philadelphia, county of Philadelphia, and the State of Pennsylvania, has invented a new, original, and ornamental Design for a Fireplace Cabinet, of which the following is a specification, reference being had to the accompanying drawing, forming a part thereof.

The figure in the drawing is a perspective view of the fireplace cabinet showing the new design. The cabinet is adapted for housing various articles, such as a radio, talking machine, records, telephone, smoking equipment, sewing equipment, desk slide, time piece, thermometer and like articles.

What is claimed is:

The ornamental design for a fireplace cabinet as shown and described.

RICHARD J. NACHTIGALL.
